PROCESS FOR THE REMOVAL OF PHENOLS
IN A PURE STATE FROM TARS OR TAR
OILSJenő Kárpáti and Móric György Hübsch,

Serial No. 240,924, and in Hungary January 15,
1927

5 Claims. (Cl. 260—154)

It has already been attempted to remove the phenols from tars and to recover them at the same time in a pure state. Some success has been attained by the aid of chemicals but the processes concerned have not been of any practical importance since the cost of the chemicals required, which can only be recovered in part, was excessive.

Physical purification processes have also already been proposed. Thus attempts have been made to utilize for this purpose that known property of concentrated ethyl alcohol by virtue of which this latter effectively dissolves the acid constituents of the tar, particularly the phenols, while hardly dissolving the hydrocarbons. Satisfactory results could not, however, be obtained in this manner either, since on the one hand a considerable content of phenol always remained in the tar hydrocarbons thus treated, and on the other hand the alcoholic phenol solution recovered contained considerable quantities, about 20 to 25%, of hydrocarbons, thus necessitating a further chemical purification.

It has further been proposed to extract the phenols from the tar by means of superheated water. Under a pressure of about 40 atmospheres and at a temperature of about 225° success has in fact been obtained in producing very good qualitative results, but this process is entirely excluded from industrial applicability on account of the difficulties incurred in the application of very high pressures and high temperatures as well as the high costs of erection and maintenance.

According to the present invention, the raw material, tar, tar oils or other tar derivatives, is treated under a moderate superatmospheric pressure and at a comparatively low temperature with a solvent for phenols diluted with water.

It is found, for instance, that if the raw material from which phenols are to be removed is intimately mixed under moderate super-pressure, for example 1.5–6 atmospheres, and at relatively low temperature, as for example at 90–150°, with a diluted aqueous solution of a solvent of phenols, as, for example, with methyl-, ethyl- or propyl alcohol, acetone, formaldehyde or acetaldehyde and the like, and the mixture is then left alone for a short time with maintenance of the temperature and pressure, then the contents of the reaction vessel separate into two layers of which one contains the tar hydrocarbons and the other the phenols dissolved out of the tar by the aqueous solvent. If now the aqueous solvent layer containing the phenols is drawn off and cooled it divides again into two layers, an under layer consisting of pure phenols and an upper layer

which contains the aqueous solvent. Thereupon the solvent is transferred again to the tar from which the phenols are required to be removed and the process is continued until the tar remaining in the reaction vessel contains only oils which are neutral, i. e. which consist exclusively of hydrocarbons.

Researches show that the aqueous solvent, for example 20% alcohol, dissolves firstly the phenols of the strongest and then successively those of less strong acid action so that the separation of the individual phenols is possible in the course of the extraction and the application of a special fractionating process is therefore not necessary.

Any suitable solvent which on the one hand dissolves phenols better than hydrocarbons and which on the other hand is also soluble in water can be applied. The solvent essentially aids the solution of the phenol in water, that is to say, it has between the tar and the water the effect of a phenol carrier agent. To the aqueous solvent neutral salts as, for example, common salt, sodium sulphate and the like, can be added whereby as is shown by experiment the degree of purity of the extracted phenols, clearly on account of the reduction of the amount of solution of the hydrocarbons, is increased.

The process results on the one hand in the recovery of pure phenols and on the other hand in the complete freedom of the tar from the phenols.

The values of the pressure and the temperature are closely related to the selected concentration of the aqueous solvent; if a very dilute solvent is employed, pressure and temperature must be increased and conversely. On economic grounds it appears naturally to be indicated to employ limits of pressure and temperature at which special apparatus is unnecessary, the more so since it is an essential advantage of the invention that no excessively high pressure or temperature is necessary.

The process can, for example, be effected in the following manner:—

An autoclave suitably heated and provided with stirring apparatus in half filled with the tar from which the phenols are to be removed and half filled with 20% aqueous methyl alcohol. The heating is so regulated that a pressure of 6 atmospheres and a temperature of about 145° continuously prevail in the autoclave. After stirring for half an hour the separated aqueous methyl alcohol-phenol solution is, with maintenance of the pressure, transferred to a cooler connected to the autoclave. The cooler connected by a pipe to a collecting flask, as, for example, a Florence flask, in which the contents of the cooler which

are still under pressure are drawn off. The liquid on settling separates in the collecting vessel into an underlayer consisting of phenols and an upper aqueous methyl alcohol layer. The latter is 5 pumped back into the autoclave and the phenols are led off separately in fractions or together.

The process can also be effected in a continuous manner, as, for example, with the application of several autoclaves and coolers in which case on 10 the one hand the tar and on the other hand the aqueous solvent are maintained in uninterrupted circulation. Instead of employing stirring the two liquids can be introduced from opposite directions and also atomizers, heat exchangers and the like, 15 can be employed. Since further the system can be constructed entirely enclosed, losses of solvents are almost completely avoidable. Mixtures of the aqueous solution of different solvents can also be employed.

20 What we claim and desire to secure by Letters Patent, is:—

1. Process for removing phenols in a pure state from tars and tar oils by treating said substances under a moderate superpressure not exceeding 6 25 atmospheres and at a moderately elevated temperature of 90 to 150° C. with an aqueous solution of a phenol solvent, allowing the mixture to stand until it separates into two layers, removing the aqueous solvent layer which contains the dissolved phenols, causing the liquid of said layer by release of the pressure and cooling to separate into two layers consisting of phenols and aqueous solvent respectively, and then removing the phenols.

30 2. Process for removing phenols in a pure state from tars and tar oils by treating said substances under a moderate superpressure not exceeding 6 atmospheres and at a moderately elevated temperature of 90 to 150° C. with an alcohol diluted 35 with water, allowing the mixture to stand until it separates into two layers, removing the aqueous solvent layer which contains the dissolved phenols, causing the liquid of said layer by release of the pressure and cooling to separate into two

layers consisting of phenols and aqueous solvent respectively, and then removing the phenols.

3. Process for removing phenols in a pure state 80 from tars and tar oils by treating said substances under a moderate superpressure not exceeding 6 atmospheres and at a temperature of 90 to 150° C. with an aqueous solution of a phenol solvent comprising about 20% alcohol and 80% water, allowing the mixture to stand until it separates into two layers, removing the aqueous solvent layer which contains the dissolved phenols, causing the liquid of said layer by release of the pressure and cooling to separate into two layers consisting of phenols and aqueous solvent respectively, and then removing the phenols.

4. Process for removing phenols in a pure state 85 from tars and tar oils by treating said substances under a moderate superpressure not exceeding 6 atmospheres and at a temperature of 90 to 150° C. with an aqueous solution of a phenol solvent in conjunction with a neutral mineral salt, allowing the mixture to stand until it separates into two layers, removing the aqueous solvent layer which contains the dissolved phenols, causing the liquid of said layer by release of the pressure and cooling to separate into two layers consisting of phenols and aqueous solvent respectively, and then removing the phenols.

5. Continuous process for removing phenols 100 from tars and tar oils and simultaneous recovery 105 of the phenols in a substantially pure state by treating said substances under a superpressure not exceeding 6 atmospheres and at an elevated temperature of 90 to 150° C. with an aqueous solution of a phenol solvent, allowing the mixture to 110 separate into two layers, removing the aqueous solvent layer which contains the dissolved phenols and causing it by release of the pressure and cooling to separate into two layers of phenols and aqueous solvent respectively, removing the phenols, and returning the aqueous solvent to the raw material to be cleaned.
